[57] CLAIM

The ornamental design for fence post formed of a recycled material, as shown and described.

DESCRIPTION

FIG. 1 is a front elevational view of the fence post formed of a recycled material, the broken lines disclosed therein are for illustrative purposes only and form no part of the claimed design;

FIG. 2 is a front elevational view of the fence post formed of a recycled material;

FIG. 3 is a rear elevational view of the fence post formed of a recycled material;

FIG. 4 is a top plan view of the fence post formed of a recycled material;

FIG. 5 is a bottom plan view of the fence post formed of a recycled material; and,

FIG. 6 is a perspective view of the fence post formed of a recycled material as viewed from the bottom thereof.
